Patented July 25, 1922.

UNITED STATES PATENT OFFICE.

FRANK E. ACKERMAN, OF ST. PAUL, MINNESOTA.

MECHANICAL HOIST.

1,423,638.

Specification of Letters Patent. Patented July 25, 1922.

Application filed August 25, 1921. Serial No. 495,191.

To all whom it may concern:

Be it known that I, FRANK E. ACKERMAN, a citizen of the United States, residing at St. Paul, in the county of Ramsey and State 5 of Minnesota, have invented certain new and useful Improvements in Mechanical Hoists; and I do hereby declare the following to be a full, clear, and exact description of the invention, such as will enable others 10 skilled in the art to which it appertains to make and use the same.

My present invention has for its object to provide an extremely simple and highly efficient mechanical hoist intended for general use but especially adapted for use in 15 connection with dumping vehicles.

To the above end, generally stated, the invention consists of the novel devices and combinations of devices hereinafter described and defined in the claims.

In the accompanying drawings which illustrate the invention like characters indicate like parts through out the several views.

Referring to the drawings:

Fig. 1 is a fragmentary side elevation of 25 a dumping vehicle in the form of a dumping vehicle in the form of a dumping truck having the invention embodied therein, some parts being indicated by means of broken lines and other parts being indicated in different positions by means of broken lines;

Fig. 2 is a plan view of the parts shown 30 in Fig. 1, with the truck body removed, certain of said parts being indicated in different positions by means of broken lines;

Fig. 3 is a transverse section taken on a line 3-3 of Fig. 1;

Fig. 4 is a detail view with some parts sectioned on the line 4-4 of Fig. 2, on an 40 enlarged scale; and

Fig. 5 is a fragmentary detail view partly in plan and partly in horizontal section, taken on the line 5-5 of Fig. 4.

Of the parts of the dumping truck illustrated it is important to note the main frame 6, rear wheel 7 and dumping body 8 mounted on a supplemental frame 9 which in turn is pivoted at 10 to said main frame.

A transverse rock shaft 11 is journaled in 50 a bearing plate 12 and a bearing 12' secured to the main frame 6 and located forward of the pivots 10. Rigidly secured to the outer ends of the rock shaft 11 are parallel and normally depending crank arms 13, the outer ends of which are connected to the supplemental frame 9 by pivoted links 14.

These links 14 are pivoted to the supplemental frame 9, forward of the rock shaft 11, and when said rock shaft is given a one-half rotation to lift the dumping body 8, 60 said links 14 and arms 13 are aligned, as indicated by broken lines in Fig. 1.

Keyed to the rock shaft 11 is a large spur gear 15 which meshes with an idle spur gear 16 journaled on a stub shaft 17 secured to 65 the bearing plate 12. Rigidly secured to the pinion 16 for rotation therewith is a spur gear 18 which meshes with a spur pinion 19, loosely journaled on a stub shaft 20 secured to the bearing plate 12. This pinion 70 19 is rigidly secured to an internal gear 21, having an intermediate radially disposed web 22 in which are formed two diametrically opposite lock openings 23. The teeth of the gear 21 are formed entirely on one 75 side of the web 22 except at the openings 23, where they are extended therethrough. Meshed with the internal gear 21 is a pinion 24 rigidly secured to an endwise moveable shaft 25 journaled on the bearing plate 12 80 and a bearing arm 26 secured to said bearing plate.

At the outer end of the shaft 25 is a hand crank 27 by which said shaft, train of gears 15, 16, 17, 19, 21 and 24 and rock shaft 11 85 may be operated to raise and lower the dumping body 8 when the shaft is adjusted to cause the pinion 24 to mesh with the internal gear 21 and the hand crank to clear 90 the side of the dumping body 8 and respective rear tire 7, as shown by full lines in Fig. 2.

It is important to note that the pinion 24 is aligned with one of the lock openings 23 in the web 22 of the internal gear 21 when 95 the dumping body 8 is down, as shown by full lines in Fig. 1. To lock the dumping body 8 down, the shaft 25 is moved endwise, as indicated by broken lines in Fig. 2 to carry the pinion 24 through the respective 100 lock opening 23. In this position of the pinion 24 the engagement of the web 22 with the shaft 25 will securely lock the dumping body 8 down. When the dumping body 8 is in a dumping position, as shown by broken 105 lines in Fig. 1, or in an intermediate dumping position the shaft 25 may be moved endwise into one of the lock openings 23 and thereby positively secure the dumping body 8 where set. A strap loop 28 is secured to 110 the supplemental frame 9 to hold the hand crank 27 up, as shown in Fig. 2, and in this

position of said hand crank, the same is entirely under the dumping body 8 and out of the way.

To move the dumping body 8 into a dumping position it is only necessary to operate the hand crank 27 sufficiently to give the rock shaft 11 a one-half rotation and thereby bring the arms 13 from depending to upright positions in which they are aligned 5 with the links 14. When the arms 13 and links 14 are aligned, a great deal of strain is removed therefrom and all danger of buckling eliminated. The arrangement of the pivots 10 and hoisting mechanism is such as 10 to require a minimum amount of power to operate the dumping body 8. The outer ends of the stub shaft 17 and 20 are connected by a tire strap 29 which holds said shafts parallel. 15

20 The above described invention, while extremely simple and of comparatively small cost to manufacture, is thought to be highly efficient for the purpose had in mind.

What I claim is:

25 1. The combination with a vehicle having a dumping body, of a crank-shaft mounted on the vehicle and connected to the dumping body, and common means for operating the crank shaft to raise or lower the dumping 30 body and for positively locking the same in a raised position.

35 2. The combination with a vehicle having a dumping body, of a crank shaft mounted on the vehicle and connected to the dumping body, and common means for operating the crank shaft to raise or lower the dumping body and for positively locking the same in a lowered position.

40 3. The combination with a vehicle having a dumping body, of a crank shaft mounted on the vehicle and connected to the dumping body, and common means for operating the crank shaft to raise or lower the dumping body and for positively locking the same in 45 a lowered or raised position.

45 4. The combination with a vehicle having a dumping body, of a crank shaft mounted on the vehicle and connected to the dumping body, and common means for operating the 50 crank shaft to raise or lower the dumping body and for positively locking the same in an extreme raised position or a predetermined intermediate raised position.

55 5. The combination with a vehicle having a dumping body, of a crank shaft and an endwise adjustable shaft mounted on the vehicle, connections from the crank shaft to the dumping body for raising or lowering the same, means for rotating the endwise 60 movable shaft, and driving connections from the endwise adjustable shaft to the crank shaft including a co-operating gear and pinion, said endwise adjustable shaft being arranged when moved to one adjusted position to lock the gear against rotation.

6. The combination with a vehicle having a dumping body, of a crank shaft and an endwise adjustable shaft mounted on the vehicle, connections from the crank shaft to the dumping body for raising or lowering the same, means for rotating the endwise movable shaft, and driving connections from the endwise adjustable shaft to the crank shaft including a co-operating gear and pinion, said endwise adjustable shaft being arranged, when moved to one adjusted position, to carry the pinion out of mesh with the gear and lock said gear against rotation. 70 75

7. The combination with a vehicle having a dumping body, of a crank shaft and an endwise adjustable shaft mounted on the vehicle, connections from the crank shaft to the dumping body for raising or lowering the same, means for rotating the endwise movable shaft, driving connections from the endwise adjustable shaft to the crank shaft including a co-operating gear and pinion, and a hand crank on the endwise adjustable shaft, said endwise adjustable shaft being arranged, when moved to one adjusted position, to carry the pinion into mesh with the gear and position the hand crank outward of the dumping body and, when moved to another adjustable position, to carry the pinion out of mesh with the gear, lock said gear against rotation and position the hand crank under the dumping body. 80 85 90 95

8. The combination with a vehicle having a dumping body, of a crank shaft and an endwise adjustable shaft mounted on the vehicle, connections from the crank shaft to the dumping body for raising or lowering the same, means for rotating the endwise movable shaft, and driving connections from the endwise adjustable shaft to the crank shaft including a co-operating gear and pinion, said gear having a radially disposed web provided with a lock opening, said endwise adjustable shaft being arranged, when moved to one adjusted position, to project 100 into said lock opening and thereby lock the gear against rotation. 105

9. The combination with a vehicle having a dumping body, of a crank shaft and an endwise adjustable shaft mounted on the vehicle, connections from the crank shaft to the dumping body for raising or lowering the same, means for rotating the endwise movable shaft, and driving connections from the endwise adjustable shaft to the crank shaft including a co-operating gear and pinion, said gear having a radially disposed web provided with a lock opening, said endwise adjustable shaft being arranged, when moved to one adjusted position, to carry the pinion through said lock opening and itself project into said lock opening and thereby lock the gear against rotation. 115 120 125

10. The combination with a vehicle having a dumping body, of a crank shaft and

an endwise adjustable shaft mounted on the vehicle, connections from the crank shaft to the dumping body for raising or lowering the same, means for rotating the endwise 5 movable shaft, and driving connections from the endwise adjustable shaft to the crank shaft including a co-operating gear and pinion, said gear having a radially disposed web provided with a lock opening, said end-

wise adjustable shaft being arranged, when moved to one adjusted position, to carry the pinion through said lock opening and out of mesh with the gear and itself project into said lock opening and thereby lock the gear against rotation. 10

In testimony whereof I affix my signature.

FRANK E. ACKERMAN.
